CAFE TRAVERSE ROD

Kenneth M. Johnson, Kensington, Conn., assignor to The Stanley Works, New Britain, Conn., a corporation of Connecticut

Filed Dec. 23, 1965, Ser. No. 515,936
6 Claims. (Cl. 16—2)

This invention relates to a cafe traverse rod and more particularly to such a rod having a self-adjusting, self-locking grommet mounted in a curved wall thereof.

One of the objects of the present invention is to provide a cafe traverse rod having a self-locking grommet mounted in an opening in a curved wall thereof which is capable of protecting the pull cord of the rod from the irregularities such as burrs or the like which may exist in the opening. Included in this object is the provision that such a grommet is simple in design and is economical to manufacture and is self-adjusting to maintain a snug fit in the opening in the curved wall of the rod despite manufacturing tolerances and variations which may exist in the size of the opening as well as any irregularities such as burrs or the like which may exist in the latter.

Another object of this invention is to provide a grommet which can be installed by an unskilled worker without the use of tools.

Other objects will be in part obvious and in part pointed out more in detail hereinafter.

The invention accordingly consists in the features of construction, combination of elements and arrangement of parts which will be exemplified in the construction hereafter set forth, and the scope of the application of which will be indicated in the appended claims.

In the drawing:

FIG. 1 is a front elevation view of a cafe traverse rod incorporating this invention;

FIG. 2 is a fragmental enlarged cross sectional view taken along the line 2—2 of FIG. 1;

FIG. 3 is an enlarged bottom view of the improved grommet of the present invention;

FIG. 4 is an enlarged top view of the improved grommet shown in FIG. 3;

FIG. 5 is an enlarged end view of the improved grommets of FIGS. 3 and 4; and

FIG. 6 is an enlarged cross sectional view in fragment depicting an intermediate step in the assembly of the grommet in the cafe traverse rod.

Referring now to the drawing in which like numerals refer to like parts throughout the several views, there is shown in FIG. 1 a cafe traverse rod 10, preferably formed of metal and having generally cylindrical cross section, and having a decorative end cap or finial 12 mounted on the end thereof.

The cafe traverse rod 10 is provided with a plurality of ring glides 14 (only two of which are shown for simplicity of illustration) to which curtains or draperies may be attached by conventional hooks in the usual manner.

Adjacent the end of the cafe traverse rod 10 is an opening 16 through which passes the pull cords 18 for shifting the glides 14 to open or close the draperies or curtains in the usual manner.

As best shown in FIG. 2, the pull cords 18 pass over a pair of pulleys 20 mounted on pins 22 which in turn are supported in a pulley housing 24 secured to the rod 10.

In accordance with this invention the opening 16 in the curved wall of the cafe traverse rod 10 is lined by a grommet generally designated by the numeral 26 to shield the pull cords 18 from the sharp edges or burrs which would otherwise be presented by the opening 16 in the curved wall of the rod 10.

2

In the preferred embodiment the grommet 26 comprises an integral body formed from a firm tough semi-rigid resilient moldable plastic material such as nylon, Delrin, or the like. The grommet body includes a pair of generally parallel spaced longitudinal walls 30 which are joined at both ends by arcuate end walls 32 to form an aperture 28. The lower portions of the walls 30 and 32 are formed so as to be convexly arcuate and terminate along the outer periphery of the grommet body by a peripheral shoulder or flange 36 which extends entirely around the grommet to overlie and conceal the edges of the opening 16. The peripheral flange 36, including the end portions 34 thereof (FIG. 5), are concavely curved and have a radius of curvature substantially equal to that of the cylindrical rod 10.

Extending upwardly from the peripheral shoulder 36 is an uninterrupted wall 38 extending around the inner periphery of the grommet 26 and terminating in a top wall 40 of generally planar configuration. Laterally extending lips or projections 42 which overlie the longitudinal portions of shoulder 36 form a pair of side grooves 44. It will be observed that the side grooves 44 are canted at an angle relative to the transverse plane through the center of the grommet due to the curvature of peripheral flange 36 so that the peripheral shoulder 36 lies tightly against the curved surface of the rod 10 to avoid leaving an unsightly gap. The width of the slot 44 likewise conforms to the thickness of the metal forming the rod 10 to provide a snug fit.

To apply the grommet 26 to the opening 16 of the rod 10 from the outside thereof, one of the lateral grooves 44 is applied over a longitudinal edge of the opening 16 as shown in FIG. 6 by moving it laterally with respect thereto and thereafter it is moved to the position shown in FIG. 2 by forcing the exposed lip 42 which remains external of the opening 16 to pass the associated side edge of the opening 16. This may be conveniently accomplished by means of thumb pressure applied to the lower surface of the grommet 26. Passage of the lip 42 through the opening 16 despite the greater dimension of the lip 42 when compared to the opening 16 is characterized by deformation of the lip 42 as permitted by the inherent flexibility thereof and is facilitated by the curved configuration of the wall of the rod 10 forming the opening 16 since the pressure applied to the grommet 26 tends to flatten out the wall and hence increase the width of the opening 16.

When the grommet 26 is finally in its assembled position as shown in FIG. 2, the shoulder 36 of the grommet 26 will firmly and closely engage the lower side of the edges of the opening 16 around its entire periphery due to the concave curvature thereof. Additionally, the lips 42 will be snugly and resiliently engaged with the inner surface of rod 10, since the lips 42, when in a natural or unflexed state are dimensioned so as to slightly interfere with the inner surface of the rod 10.

It will be observed, as best shown in FIG. 2, that the grooves 44 are canted and their bottom walls are spaced apart a lesser distance than the width of the opening 16 to accommodate any burrs or other constructional irregularities which might exist in the walls of the rod 10 around the opening 16 thereby permitting the semi-rigid grommet 26 to be snugly seated despite dimensional variances and imperfections in the opening 16. Additionally it will be seen that the grommet of the present invention is of durable and lightweight construction which may be manufactured at low cost, and which may be easily and rapidly inserted into the pull cord opening of a cafe rod having curved walls by unskilled labor with substantially no risk of damage to the surface finish of the cafe rod.

As will be apparent to persons skilled in the art, various modifications and adaptations of the structure above described will become readily apparent without departure from the spirit and scope of the invention, the scope of which is defined in the appended claims.

I claim:

1. In combination with a cable traverse rod having a pull cord opening in a curved wall thereof wherein variances occur in the dimensions and finish of the openings, a self-adjusting, self-locking grommet for covering the edges of said opening comprising an apertured body having generally parallel side walls joined together at their ends by curved end walls, the body having a convex bottom surface terminating on the outer periphery thereof to form a peripheral flange around the periphery of the grommet, the transverse portions of the peripheral flange being concavely curved and having a curvature corresponding to the curvature of the rod at the end of said opening, the grommet further having a continuous inner peripheral wall projecting upwardly above said shoulder and disposed within said opening, said inner peripheral wall providing a pair of laterally extending lips on the sides of said grommet spaced from the peripheral flange to form a pair of grooves therewith, said laterally extending lips being formed of a resilient semirigid molded plastic deformable to alter the lateral projection of said lips for assembly in said opening and to resiliently bias said peripheral flange in intimate contact with the curved outer periphery of said rod.

2. A device as recited in claim 1 wherein said pair of grooves are canted relative to a transverse plane through said grommet.

3. A device as recited in claim 1 wherein the longitudinal portions of said peripheral flange have a curvature essentially conforming to that of the periphery of the rod at the edge of said opening.

4. A device as recited in claim 3 wherein said grommet is formed of molded nylon.

5. For lining an opening in a curved wall of a traverse rod wherein variances occur in the dimensions and finish thereof, a moulded self-adjusting, self-locking grommet comprising an apertured body having generally parallel longitudinal side walls joined together at their ends by curved end walls, a continuous peripheral flange formed on the outer periphery of the grommet, the end portions of said peripheral flange being concavely curved and having a curvature corresponding with the curvature of the traverse rod at the end of said opening, said grommet further having a continuous upstanding inner peripheral wall providing a pair of outwardly extending lips on the sides thereof, said laterally extending lips being spaced from the peripheral flange to form a pair of side grooves therewith, said grommet being composed of a resilient semirigid molded plastic flexible to alter the lateral projection of said lips during assembly in said opening.

6. A device as recited in claim 5 wherein said pair of grooves are canted relative to a transverse plane through the center of said grommet.
